UNITED STATES PATENT OFFICE.

BERTRAM J. GOLDSMITH, OF NEW YORK, AND EMIL KOEB, OF TUCKAHOE, NEW YORK,
ASSIGNORS TO PERFECT WINDOW REGULATOR CORPORATION, OF LONG ISLAND
CITY, NEW YORK, A CORPORATION OF DELAWARE.

WINDOW MOUNTING.

Application filed March 26, 1925. Serial No. 18,631.

This invention relates to the mounting of windows and is particularly adapted for use in closed automobile constructions.

It is a primary object of the invention to provide a construction which facilitates mounting of the widow and which will operate satisfactorily when the window has been installed.

It is a further object to provide a rigid guiding channel from which the window glass can be extracted without splitting the channel at the belt.

Other and more specific objects will appear from the following description.

15 In the drawings:

Fig. 1 is an elevational view of a portion of an automobile door showing our invention applied thereto.

Fig. 2 is a section on the line 2—2 of 20 Fig. 1.

Fig. 3 is a section on the line 3—3 of Fig. 1.

Figs. 4 and 5 are broken sections similar to Fig. 2 showing the method used for 25 moving and installing the window.

Fig. 6 is a detail sectional view on the line 6—6 of Fig. 1.

Referring to the details of the drawings, there is shown in Fig. 1 an automobile door

30 provided with the usual window opening 12 and window well 14. While we have shown the invention throughout as applied to an automobile door, it is obvious that the invention is not so limited but that it has 35 various uses and may be employed with any other kind of supporting frame.

The window or closure 16 is adapted to be slidably supported on the frame member 10, the movements thereof being controlled 40 by the window regulator 18 engaging, as at 20, with a controlling member carried by the window. This particular construction forms no part of our present invention and any other form of window regulator may be 45 used if desired. The door may be provided with any preferred door latch indicated generally at 22.

We have designed an improved mounting for the window 16 constructed as follows:

50 The side members 24 of the frame member 10 are cut away as at 26 to provide

pockets for receiving the window guides 28. The guide members 28 according to this invention are drawn on the arc of a circle and terminate short of forming a complete circle. The free edges of said members may be inturned to provide reinforcing flanges 29, and are spaced so as to leave the longitudinally extending opening 30 for the window. The interior of the guide members 55 are preferably provided with distortable packing material 32 to prevent any noise during the use of the window and to protect the same against breakage, the packing material being held against dislocation by 60 means of the inturned flanges 29. The guide members 28 are held in place by the molding strips 34 which engage and clamp the guide members in their set positions. Additional securing elements in the form of 70 plates 36 engaging the lower end of the guide members form with the side member 24 and molding strip 35 a complete enclosure for the lower end of the guide members. The plates 36 in the construction shown are 75 formed with outstanding arms 37 provided with abutting pads 38 upon which the window or the operating member carried thereby may rest when the window is in lowered position.

80 It will be observed that the window is of less width than the distance between the rotative axes of the channels 28 and that the slotted openings in the packing material 32 permit the insertion and removal of the window as described below.

The window is mounted in position on the frame as follows:

85 After the main body of the frame member 10 has been constructed and the guide members 28 placed in position on the side sills of the door, the guide members are held in position by the plate 36. The guide members are then moved to the position shown in Fig. 5 and the window is inserted into 90 the position shown in said figure so that, upon rotation of the guide members 28 to the position shown in Fig. 4, the window is 95 securely held against displacement in any way except for its normal operating movements. The molding strips 34 are then secured in position so as to bear tightly 100

against the guide members 28 and the window is ready for use. The window may be removed at any time by rotating the channels 28 to the position shown in Fig. 5. This may be accomplished as by means of a tool shown in dotted lines in Fig. 4.

It will be seen from the above description that the window need not be placed in the frame until the door has been otherwise substantially completed. This avoids any likelihood of the window being broken as would be the case if the window were mounted in position as the door was being constructed. The guide members 28 are held rigidly in the position shown in Fig. 4 and effectually prevent escape of the window, its only possible movement being in a vertical direction to open or close the window opening 12.

Having now described our invention we desire it to be understood that the embodiment shown is merely illustrative and that we are limited only as set forth in the appended claims.

We claim as our invention:

- 25 1. In combination with a frame member having a window opening therein, a window adapted to be movably supported therein, means for supporting and guiding said window therein, said means comprising rotatable guide members carried by the frame member and having longitudinally extending openings constructed to receive said window when said guide members are rotated to abnormal positions, said window being held against removal by said guide members when the latter are rotated to their normal operative positions.
- 30 2. In combination with a frame member having a window opening therein, a window adapted to be movably supported therein, means for supporting and guiding said window therein, said means comprising rotatable guide members carried by the frame member and having longitudinally extending openings constructed to permit the insertion of said window thereinto when said guide members are rotated to abnormal positions, said window being held against removal by said guide members when the latter are rotated to their normal operative position, said guide members containing shock absorbing packing material positioned between said guide members and said window.
- 35 3. In combination with a frame member having a window opening therein, a window adapted to be movably supported therein, means for supporting and guiding said window therein, said means including a substantially rigid rotatable guide member, means for rotatably supporting said guide member on said frame member, said guide member having a longitudinally extending opening constructed to permit the insertion of said window thereinto when said guide member is

rotated to an abnormal position, said window being held against removal by said guide member when the latter is rotated to its normal operative position and means for holding said guide member normally in fixed position.

4. In combination with a window frame having a window opening therein, a window adapted to be movably supported therein, means for supporting and guiding said window therein, said means comprising rotatable guide members carried by said window frame and having longitudinally extending openings to receive said window when said guide members are rotated to one position, said window being held against removal by said guide members when the latter are rotated to their normal operative position, clamping strips engaging said guide members to hold them normally in fixed position, and additional clamping elements partially encircling said guide members.

5. In combination with a window frame having a window opening therein, a window adapted to be movably supported therein, means for supporting and guiding said window therein, said means comprising rotatable guide members carried by said window frame and having longitudinally extending openings to receive said window when said guide members are rotated to one position, said window being held against removal by said guide members when the latter are rotated to their normal operative position, clamping strips engaging said guide members to hold them normally in fixed position, additional clamping elements partially encircling said guide members and stop members for said window carried by said additional clamping elements.

6. In a window mounting, a window guide comprising a plurality of metallic casings provided with slotted openings for receiving said window, and means permitting the rotation of one of said casings about a longitudinal axis, the opening in said last-named casing being of greater width than the thickness of said window to permit the removal of said window from said casing when the latter has been rotated.

7. In a window mounting, a window guide comprising a hollow metallic casing provided with a slotted opening for receiving said window, means for movably supporting said casing, said means permitting the rotation of said casing about a longitudinal axis, shock absorbing packing material positioned within said casing in position to be engaged by a window inserted into the same, said packing material serving to space said window from said metallic casing.

8. In a window mounting, a window guide comprising a hollow metallic casing provided with a slotted opening for receiving said window, supporting means for said

casing, said means permitting the rotation of said casing about a longitudinal axis while in its normal operative location, shock absorbing packing material positioned within said casing and formed with a longitudinal guideway, the edges of said casing adjacent said opening terminating in inwardly turned angular extensions constructed to reinforce said edges and to engage said packing material to prevent displacement thereof, said extensions being normally spaced from said window.

9. In combination with a rigid window frame, a window, means for supporting said window on said frame member, said means comprising channels rotatably mounted on said frame member and provided with slotted openings for receiving said window, said window being of less width than the distance between the rotative axes of said channels, whereby said window may be bodily removed from said channel by rotation of said channels.

10. In combination with a window frame, a window guide comprising a substantially cylindrical metallic casing provided with a longitudinally extending opening for receiving said window, releasable means for fixedly securing said window guide to said frame member for preventing displacement

thereof and means for normally spacing said window from said casing.

11. In combination with a frame member, a substantially rigid window channel formed with means for engaging and supporting a window thereon, and means for rotatably supporting said channel on said frame member for rotation about a longitudinal axis.

12. In combination with a window frame, metallic guide members, means for rotatably supporting said guide members on said frame and releasable molding strips secured to said window frame and engageable with said guide members for holding said guide members in fixed position.

13. In combination with a rigid window frame, slotted window guides permanently mounted on said frame and capable of rotation about longitudinal axes, a window 50 slidable in said window guides, said window being insertible into or removable from said guides when the latter are rotated to abnormal positions.

Signed at New York in the county of 55 New York and State of New York this 25th day of March, A. D. 1925.

EMIL KOEB.
